[57] CLAIM

The ornamental design for a water faucet, as shown and described.

DESCRIPTION

FIG. 1 is a perspective view taken from the top, front and left side of a water faucet showing my new design; FIG. 2 is a front elevational view thereof;

FIG. 3 is a bottom plan view thereof;

FIG. 4 is a left side elevational view thereof, the right side being a mirror image of the left side;

FIG. 5 is a top plan view thereof; and,

FIG. 6 is a rear elevational view thereof.

FIG.1

FIG.2

FIG.3

FIG.4

FIG.5
